UNITED STATES PATENT OFFICE

95,947

DESIGN FOR A COMBINATION ASH TRAY AND SALTCELLAR STAND

Monty J. Buchanan, Seattle, Wash.

Application March 25, 1935, Serial No. 56,044

Term of patent 7 years

To all whom it may concern:

Be it known that Monty J. Buchanan, a citizen of United States, residing at Seattle, in the county of King and State of Washington, has invented a certain new, original, and ornamental Design for a Combination Ash Tray and Saltcellar Stand, of which the following is a specification, reference being had to the accompanying drawing, forming part thereof.

The figure is a perspective view of a combination ash tray and saltcellar stand, showing my new design.

I claim:

The ornamental design for a combination ash tray and saltcellar stand, as shown.

In witness whereof, I have hereunto subscribed my name this 18th day of March A. D. 1935.

MONTY J. BUCHANAN.
